UNITED STATES PATENT OFFICE.

ROBERT E. POINDEXTER, OF INDIANAPOLIS, INDIANA.

DESIGN FOR A FENCE-PANEL.

SPECIFICATION forming part of Design No. 24,514, dated July 30, 1895.

Application filed March 7, 1895. Serial No. 540,894. Term of patent 3½ years.

To all whom it may concern:

Be it known that I, ROBERT E. POINDEXTER, a citizen of the United States, residing at Indianapolis, in the county of Marion and State of Indiana, have invented and produced a new and original Design for a Fence-Panel, of which the following is a specification, reference being had to the accompanying drawing, showing a fence-panel.

5 The leading features of my design consist in a plurality of horizontal wires arranged in parallel series, each of said wires consisting of a plurality of strands which are twisted together into a cable or rope-like construction; 10 also transverse stays joined together at the top into pairs, the two stays of each pair being crimped in opposite directions at the points of intersection of the stays with the horizontal wires, and the said horizontal wires, 15 midway between the intersecting points of the stays with the wires, having its strands expanded to form a geometrical opening or pattern.

20 A are the horizontal wires, and may be of

any desired number, according to the height 25 of the fence. They will be constructed from a plurality of strands, which are twisted together in order to present a more ornamental and pleasing appearance.

B and B' are the stays which are joined together by the integral connection B². They will be constructed from a plurality of wires twisted together to afford an easier and more pleasing effect than could be had with a straight wire, and the ornamentation is increased additionally by providing the crimps 35 b at the intersections of the stays with the horizontal wires. The expanded portions in the horizontal wires are shown at a.

What I claim is—

40 The design for a fence panel, as herein shown and described.

In testimony whereof I affix my signature in presence of two witnesses.

ROBERT E. POINDEXTER.
